UNITED STATES PATENT OFFICE.

SEBASTIAN HINTON, OF WINNETKA, ILLINOIS, ASSIGNOR TO JUNGLEGYM, INC., OF CHICAGO, ILLINOIS, A CORPORATION OF ILLINOIS.

CLIMBING STRUCTURE.

Application filed October 1, 1920. Serial No. 414,031.

To all whom it may concern:

Be it known that I, SEBASTIAN HINTON, a citizen of the United States, and a resident of Winnetka, Illinois, in the county 5 of Cook and State of Illinois, have invented certain new and useful Improvements in Climbing Structures, of which the following is a specification.

This invention relates to climbing apparatus, for children. It is an object of the invention to provide for playgrounds or the like, or for athletic establishments, in general, an apparatus wherein the manifest advantages of climbing as an exercise can 10 be freely utilized and made available, while the dangers incident to miscellaneous climbing, such as tree climbing or the like, can be minimized.

In a co-pending application, Serial No. 20 398,178, filed July 22, 1920, patented October 23, 1923, No. 1,471,465, I have disclosed an illustrative climbing apparatus comprising a structure made up of outline cubes or in other words, a reticulated structure 25 so proportioned and designed as to permit climbing in any direction. The structure there shown was fabricated out of cut-to-length oppositely threaded pipe and has been employed with great success.

30 In the drawings, which represent an illustrative embodiment of the invention;

Fig. 1 is an elevation of a climbing structure, made in accordance with the invention,

Fig. 2 is an enlarged perspective view of 35 one corner thereof,

Fig. 3 is a broken out elevation, showing a compression member,

Fig. 4 is a perspective view, separated out, showing one of the central couplings 40 and associated climbing elements,

Fig. 5 is a cross sectional view showing certain details of the coupling construction, and

Fig. 6 is a cross sectional view of one of 45 the climbing bars, showing a groove therein to house a tie wire.

The structure as a whole is a reticulated rectangular structure which may be made of any desired size, provided its proportions are practical. It comprises a series

of vertical elements referred to generally by reference character 1, and two series of horizontal elements referred to generally by reference characters 2 and 3, Fig. 2, the series of elements 2 being preferably at 55 right angles to series 3.

The structure is so designed that a boy, for instance, of eight years old, may make a diagonal climb from one horizontal climbing element above, in the next adjacent vertical plane; the climb being facilitated by grasping the horizontal climbing element above that to which the climb is made.

In an illustrative form of the apparatus, which has been in actual use, the horizontal 60 elements are spaced two feet apart, horizontally and vertically. I have found, however, that children seem to like to climb through the structure to some particular point and there swing head downward by 65 the knees, calling back and forth to each other, a trick which can be explained of course only by the monkey instinct.

The present illustrative form of the structure is designed to afford greater opportunities for this, as well as to permit lateral progress through the structure, somewhat more easily than that possible with the structure in which the cubes are two feet on a side. Thus, referring to Fig. 2, 70 I make the horizontal bars 2 and 3, comprising the bars in each vertical plane, three feet apart, and I stagger these bars in adjacent parallel vertical planes so that the distance between parallel adjacent bars, in 75 adjacent vertical planes will be a foot and one half in a vertical direction. Thus the vertical distance between the outside bar 3' and the bar 3, (Fig. 2) is one and one half feet and the distance between the bars 2 and the adjacent bars 2', (Fig. 2) will 80 also be a foot and one half in a vertical direction, this relationship being preferably persisted in throughout the entire structure no matter what its size, and being varied only at the top and bottom where additional bars such as 2² are inserted to make 85 the structure level.

In this form of apparatus, an eight year old boy, being approximately four feet high, 100

can easily duck through the three feet space between superposed horizontal bars, while at the same time he can readily make the diagonal climb previously referred to. He 5 can also comfortably swing by his knees from any of the horizontal bars, without hitting his head on the horizontal bar immediately below.

In the structure herein disclosed, I make 10 the horizontal distance, or length of the horizontal climbing elements 2 and 3, two feet. Thus the horizontal unit in the illustrative structure herein disclosed is two feet, the vertical unit is three feet, and the climbing 15 unit, is a diagonal climb, on a diagonal whose base is two feet and whose vertical side is one and one half feet,—in other words the climb between the lower element 3' (Fig. 2) and the next element 3 above it. 20 I shall now more specifically describe the structure shown in the drawings. For the verticals 1, I preferably employ throughout, oppositely threaded pipe sections. By examination of the structure shown in Fig. 2, 25 (which will reveal that structure better than a description), it will be seen that every alternate vertical support will be made in three foot lengths with couplings at the top and bottom, as shown at 1, 1' in Fig. 2.

30 The couplings used with the verticals 1, 1' will be six way couplings 4, in the interior of the structure, and four way angle couplings on the corners as indicated at 4' and four way plain crosses at the top and bottom 35 as indicated by 4², all couplings being oppositely threaded in the vertical run.

Of course six way couplings could be used throughout, if desired; that is in the place of the couplings 4' and 4² and all the 40 surface couplings correspondingly modified, to permit additions to the structure after it is first erected.

The other series of vertical members will comprise pipe lengths 12 one and one half 45 feet in length or rather of such a length that two thereof and the intervening coupling 5 will make up a length equal to the length of the three foot couplings 1'. With this series of verticals, the couplings will be plain

50 crosses such as shown at 5, throughout the structure and other plain crosses or T's such as shown at 5' on the surface, and four way angle crosses, such as shown at 5² at the corners.

55 I will now describe the couplings employed. The outside couplings, i. e. those couplings upon the four vertical sides and the top of the structure, will be oppositely threaded in each run and the associated 60 horizontal bars 2', 2², and 3', Fig. 2, will be oppositely threaded steel pipe to correspond. Thus the entire outer wall or skin of the structure will be fabricated out of oppositely threaded pipe and couplings to 65 match.

The interior couplings such as 4, whether six way couplings, as there shown, or four way couplings 5, will be cast to correspond to the shape shown in Fig. 4, and oppositely threaded in the vertical run only as shown 70 at 6.

These interior couplings are not designed to hold pipe, but wooden climbing bars, such as shown in Fig. 4, and are therefore cast to present at the end of each run a 75 socket 7, having a shoulder 8, against which bears the end of the climbing element 2 or 3.

The socket 7 is formed with an extension 10 underlying the bottom of the climbing element, to give it substantial support 80 against downward strains.

The climbing elements 9 are of peculiar conformation, more or less egg shaped in cross section, as shown in Fig. 4, and are preferably made of wood, as for instance of 85 oiled hickory, which is strong, agreeable to climb, slightly resilient, and practically weatherproof.

They are made in the cross sectional form shown to produce several desirable results. First, and important: this shape is easier to grasp. It also provides the maximum strength against the downward force of the weight of the climbing child with an economy of material, its horizontal dimension being less than its vertical dimension. It further provides a desirable resiliency, 95 particularly against horizontal impacts. In other words, climbing bars of this character, particularly if made of wood, will yield 100 enough if heavily bumped, considerably to relieve the shock. It will be understood that it will be practically impossible for a child to fall head-on and vertically on one of the climbing bars 3. He can, however, if he falls, hook by his knees or toes on one climbing bar, so that his head swings in an arc 105 up against another of the climbing bars.

If this happens, and the child's head strikes the bar (in a more or less horizontal direction), the bar will flex enough to relieve the shock and avoid the injury, which might conceivably result if a piece of steel pipe 110 were in its place.

Furthermore, by some sort of a suitable bending apparatus more powerful than the strength of the child, a bar of the shape shown in Fig. 4 can be bowed or flexed in a plane of its narrow cross sectional dimension and snapped into place in the structure in lieu of one which has splintered, broken, or which for any other reason it is desirable to replace.

The assembly of a construction of the type shown will be exceedingly simple. Thus, for instance, two adjacent outer walls can be erected of oppositely threaded pipe. After this the roof or ceiling may be put on. The verticals may be put together on the ground and suspended in the ceiling, 125 130

certain thereof extending into holes in the ground, in which they may be blocked up on a brick or stone to support the ceiling. When all the verticals are in place, the 5 climbing elements 2 and 3 can be inserted by springing the verticals apart enough at each coupling to permit this. There the two remaining sides can be put on, of oppositely threaded pipe. After this by going over 10 the outer layer, or skin of the structure, comprising the four walls and the top, with a pipe wrench this skin can be shrunk to put the interior under very heavy compression. The compression so produced 15 will cause the climbing bars 3 and 2 to abut so firmly against the shoulders 8, in their sockets, that they can never be pulled out by a child, and they will brace the verticals from all sides.

20 However, if it be found to be desirable to add additional ties toward the center of each vertical wall this may be done in the manner shown in Fig. 3, wherein a heavy tie wire 11 is employed, which is housed in 25 a groove shown at 12 in the bottom of the climbing members 3 and 2, this tie wire passing entirely through all of the vertical pipes and couplings and being tightened at the end by turn buckles or nuts, such as shown 30 at 13. As many of these ties can be placed across the structure as desired, though it is not believed that any will be necessary, except possibly in a very large structure. After the structure has been thus tightened 35 up, the holes in which the verticals rest can be filled with concrete. Of course other methods of erection may be employed.

I make considerable point of the great strength of the structure, as this is important. Thus most persons have seen a monkey in a zoo, seize the bars of his cage with hands and feet and throw his body violently back and forth, other monkeys following suit. Children, in the structure I 45 have erected, do the same thing, apparently unconscious of any imitation of monkeys. It can be appreciated that with twenty-five or thirty heavy boys doing this, the strain on the structure is very great. In the structure herein disclosed the walls and top are extremely strong, being made of oppositely threaded fabricated pipe turned up tight. The verticals are of pipe rigidly secured at their tops in the top or ceiling of the structure and many of them sunk in concrete at their base. All of them are braced either every three feet or every foot and a half by climbing elements 2, 3, which impinge 55 against the verticals or four sides under heavy pressure. The structure is then made strong enough to stand severe strains which for safety's sake is extremely desirable.

Crossed ropes 14 can be employed at the bottom of the structure, and as much as desired upward from, say, about the level of 60 six feet, including the top, can be covered with ordinary fence wire, if desired, to prevent children falling off the outside of the structure. This has been omitted from the drawings as it would confuse them. It is 70 not believed that either of these precautions will be necessary, as a child falling in the structure will have so many opportunities to catch a bar or vertical that it is almost impossible that he will fall through it to 75 the ground.

The structure herein shown is extremely efficient for supervised athletic work. Thus 80 classes of children can be put into one of these structures and made to take almost any conceivable exercise. The structure is compact and can be employed on the most limited playground. In order further to improve the efficiency with a class of children, I have used on the level of three and 85 six feet above the ground, an alternately spaced five way coupling, instead of four, or six way instead of five on the outside of the structure. In the extra threaded socket thus provided, the bars 15 are tightly 90 screwed, and are connected by a rail 16, shown in cross section. Additional diagonal braces may of course be employed to support this bar 15. These bars form chin- 95 ning bars on which an entire class of children can take chinning exercises as a part of various tests or exercises customarily used in supervised athletic work. It has been a problem in this field heretofore, to find adequate means whereby a large number of children can all chin themselves at 100 once in competition.

Having now described my invention, I claim:

1. A reticulated climbing structure for 105 children, comprising supports, having sockets therein, wooden climbing bars extending in a plurality of directions and spaced and arranged to permit climbing from one to another in a plurality of selective dimensions from points within the structure, said bars fitting at their ends in said sockets, and means for preventing said bars from being withdrawn from the sockets.

2. In apparatus of the class described, a 110 plurality of vertical supports, a plurality of wooden climbing bars, arranged at right angles and so spaced as to permit elective climbing in a plurality of dimensions through the structure, sockets in the vertical 115 supports, the ends of said bars being engaged in said sockets, and means to prevent the bars from turning in the sockets.

3. In apparatus of the class described; and in combination, a reticulated climbing structure, comprising in combination, an outer layer of metal pipe and couplings, said pipe and couplings being oppositely threaded; an inner body comprising horizontal wooden climbing elements and vertical supports con- 120 125 130

nected by slip joints, whereby the inner body can be put into compression by tightening up the pipe.

4. In apparatus of the class described, a plurality of vertical supports, climbing elements connected to said supports, all so arranged as to permit climbing electively in three dimensions from points within the ap-

paratus, the climbing elements resting upon and supported by trough shaped extensions 10 from the vertical supports.

In witness whereof, I hereunto subscribe my name this 22 day of September, A. D. 1920.

SEBASTIAN HINTON.
